UNITED STATES PATENT OFFICE.

ROBERT W. WIEDERWAX, OF ATLANTIC CITY, NEW JERSEY, ASSIGNOR TO GEIST MANUFACTURING COMPANY, OF ATLANTIC CITY, NEW JERSEY, A CORPORATION OF DELAWARE.

OIL BURNER.

Original application filed July 25, 1921, Serial No. 487,534. Divided and this application filed April 13, 1922, Serial No. 552,268.

To all whom it may concern:

Be it known that I, ROBERT W. WIEDERWAX, a citizen of the United States, residing at Atlantic City, in the county of Atlantic and State of New Jersey, have invented certain new and useful Improvements in Oil Burners, of which the following is a specification.

This invention relates to oil burners, and 10 is a division of my co-pending application Serial No. 487,534, filed July 25, 1921.

In the said application, I have disclosed an improved type of burner, consisting of a casing forming a combustion chamber, the 15 rear of the casing being open to permit introduction of air. The front of the casing is reduced in cross section and a vaporizing retort is formed within the walls of the reduced portion. This reduced portion is so 20 designed that the flame from the burner will strike the walls of the combustion chamber at the rear end of the reduced portion, whereby the entire vaporizing retort is subjected to a high temperature and the oil immediately 25 vaporized.

In the ordinary type of oil burner, the retort is generally formed in a coil. The oil passes into this coil and is partially gasified. This gas, being lighter than oil, attempts 30 to rise to the top, but it is impossible for the oil and gas to separate while flowing around the coils. This mixture of oil with the vapor causes a lowering of temperature to such an extent that complete combustion is 35 impossible and deposition of carbon results.

In the present invention, the oil passes into a retort which is maintained at a very high temperature and is immediately vaporized. A uniform temperature is maintained 40 throughout the retort and mixture of oil and vapor is prevented as the oil is vaporized as soon as it passes into the retort. This gives a vapor which burns without deposition of carbon. The burner construction 45 above described is shown but not claimed in my co-pending application, and forms the subject matter of the present application.

An object of the invention is the provision of an oil burner in which the oil will be 50 completely and properly vaporized before being admitted to the burner.

A further object is the provision of a burner casing in which the vaporizing retort

is arranged at the front of the casing in the zone of high heat.

In the accompanying drawings, I have shown one embodiment of the invention. In this showing:

Figure 1 is a central vertical sectional view of the burner,

Figure 2 is a horizontal sectional view on line 2—2 of Figure 1, and,

Figure 3 is a vertical sectional view through the vaporizing retort, on line 3—3 of Figure 1.

Referring to the drawings, the reference numeral 1 designates a burner casing which is substantially circular in cross section at the rear and is open, as indicated at 2, for the admission of air. The top and bottom walls 70 of the casing converge toward the front, as indicated at 3, and the side walls diverge, as indicated at 4, providing a broad outlet 5, of restricted height. The burner casing may be arranged on a suitable support 6.

A retort space 7 is provided in the front portion of the burner casing and this retort space communicates with a main oil feed pipe 8. The oil may be delivered through the pipe to the retort by any suitable means, as by pressure. The retort is provided with an outlet pipe 9, communicating with a valve casing 10, arranged at the rear of the casing. As shown, the valve casing is provided with a nozzle 11, having a needle valve 12 85 therein. The needle valve is controlled by a suitable handle 13. The line of flame projecting from the burner is indicated by dotted lines 14, in Figure 1 of the drawings.

In operation, fuel to be burned is delivered 90 to the retort 7 through pipe 8. The provision of a retort arranged entirely at the front of the casing, forwardly of the point where the flame strikes the walls of the casing insures a temperature within the retort 95 sufficiently high to immediately vaporize the oil. This provides a fuel which will burn properly without deposition of carbon.

It will be apparent that the vaporizing chamber or retort is highly heated by the 100 flame from the burner and the oil is vaporized as soon as it reaches the retort. There is no oil present at any time within the retort and mixture of oil and vapor is prevented. In addition, the oil enters at the 105 bottom and the vapor is removed at the top.

The vapor being lighter than the oil, flows freely to the top and there is no tendency to carry oil into the burner mixed with the vapor. A substantially uniform temperature is maintained at all times in the retort. The provision of a vaporizing chamber having a relatively uniform temperature further eliminates variance in pressure due to improper vaporization as is obtained when the retort extends rearwardly into the cooler portion of the combustion space. I have found by experiments that a vaporizing chamber arranged in the walls of the burner casing and disposed forwardly of the point where the flame strikes the walls provides a burner by means of which a higher temperature may be obtained than in a construction where the retort extends rearwardly of the point where the flame strikes the walls. As stated, the deposition of carbon is reduced to a minimum and the length of time that a burner may be operated without stopping to remove carbon from the burner casing is materially increased. It is to be understood that the form of my invention herewith shown and described is to be taken as a preferred example of the same, and that various changes in the shape, size, and arrangement of parts may be resorted to without departing from the spirit of my invention or the scope of the subjoined claims.

Having thus described my invention, I claim:

1. A burner comprising a casing forming a combustion chamber, a nozzle mounted adjacent the rear of said casing, a vaporizing retort surrounding said casing and terminating at substantially the point where the flame from said nozzle strikes the wall of said casing, a feed pipe connected to said retort exteriorly of said casing, and a pipe connecting said retort and said nozzle, said pipe extending exteriorly of said casing.

2. A burner comprising a casing forming

a combustion chamber, the rear of said casing being open for the introduction of air, the forward end of said casing being formed of double walls to provide a vaporizing retort, a feed pipe connected to said retort exteriorly of said casing, a nozzle mounted in the rear of said combustion chamber, a pipe connecting said retort to said nozzle, said pipe extending exteriorly of said casing, and means for directing the flame from said nozzle against the wall of the combustion chamber adjacent said retort.

3. A burner comprising a casing forming a combustion chamber, the rear end of said casing being open, the forward end of said casing being reduced and provided with spaced walls to form a vaporizing retort, a feed pipe connected to said retort exteriorly of said casing, a nozzle arranged adjacent the rear of said combustion chamber, and a pipe connecting said retort and said nozzle, said pipe extending exteriorly of said casing, said retort terminating at substantially the point where the flame from said nozzle strikes the wall of the combustion chamber.

4. A burner comprising a casing forming a combustion chamber, a nozzle arranged adjacent the rear of said combustion chamber, the walls of said casing converging vertically forwardly of said nozzle and diverging horizontally to provide a broad outlet of restricted height, a vaporizing retort surrounding the forward end of said casing, said retort terminating at substantially the point where the flame from said nozzle strikes the wall of the combustion chamber, means for conveying fuel to said retort, and means for conveying vaporized fuel from said retort to said nozzle.

In testimony whereof I affix my signature in presence of two witnesses.

ROBERT W. WIEDERWAX.
